UNITED STATES PATENT OFFICE

ARTHUR F. ELKINS AND HENRY HUNTER, OF IROTON, OHIO, ASSIGNEES OF ONE-FOURTH
TO FRANK L. McCaULEY AND ONE-FOURTH TO THOMAS J. KENNEDY, BOTH OF IROTON,
OHIO.

SAFETY APPLIANCE FOR MOVING-PICTURE APPARATUS.

No. 861,169.

Specification of Letters Patent.

Patented July 23, 1907.

Application filed April 6, 1907. Serial No. 366,803.

To all whom it may concern:

Be it known that we, ARTHUR F. ELKINS and HENRY HUNTER, citizens of the United States, residing at Ironton, in the county of Lawrence and State of Ohio, 5 have invented new and useful Improvements in Safety Appliances for Moving-Picture Apparatus, of which the following is a specification.

This invention relates to an improved safety appliance for moving picture apparatus, such as kinetoscopes; and it has for its object to provide a simple and 10 effective device whereby the film shall be safe guarded against igniting and exploding.

With these and other ends in view which will readily appear as the nature of the invention is better understood, 15 the same consists in the improved construction and novel arrangement and combination of parts which will be hereinafter fully described and particularly pointed out in the claims.

In the accompanying drawings has been illustrated 20 a simple and preferred form of the invention; it being, however, understood that no limitation is necessarily made to the precise structural details therein exhibited, but that changes, alterations and modifications within the scope of the invention may be resorted to when desired.

In the drawing, Figure 1 is a perspective view showing the safety appliance in position for operation. Fig. 2 is a vertical transverse sectional view of the safety appliance.

30 Corresponding parts in both figures are denoted by like characters of reference.

A designates a holder which is composed of two semi-cylindrical members 1 and 2 that are connected along their edges, at one side, by a hinge 3; the semi-cylindrical members are provided along their opposite edges with flanges 4 and 5 adapted to be connected by a fastening member such as a screw 6.

The semi-cylindrical members 1 and 2 coöperate to form a sleeve or collar wherein is mounted a tank or receptacle 7 of cylindrical shape, said tank or receptacle being formed of clear transparent glass and provided at its ends with flanges 8 abutting upon the ends of the sleeve or holder. The upper member 2 of the latter has an aperture 9 for the passage of a neck 10 that extends upwardly from the tank or receptacle, said neck, 40 which constitutes a filling aperture, being provided with a closure 11.

The lower member 1 of the sleeve or holder has a downward extending tubular shank 12 adjustably engaged 50 an arm 13 having at its lower end an eye 14 adjustably engaging a supporting bracket 15 upon which said arm 13 may be secured by means of a set screw 16. An offset screw 17 serves to secure the tubular shank 12 adjustably upon the arm 13. The supporting bracket 1

15 may be secured in any desired position by means of 55 a fastening member such as a bolt or screw 18.

In practice the tank or receptacle 7 is filled with a clear transparent liquid such as water; the holder A is then positioned intermediate the light projecting lens holder 19 and the moving film 20, so that the rays of 60 light will be projected through the liquid contained in the tank or receptacle which will to such an extent absorb the heat rays that ignition of the film will be practically impossible.

By the construction herein described, the holder A 65 may be very readily adjusted to the proper position as may be rendered necessary by varying positions of the lamp or the lens holder as well as that of the film.

The device may be readily disassembled and packed for storage or shipment; and the liquid containing tank 70 may be readily detached from the holder for the purpose of cleaning the tank or renewing the contents thereof.

Having thus fully described the invention, what I 75 claim as new is:—

1. A safety appliance for moving picture apparatus comprising a tubular holder, means for supporting said holder in position, and a transparent cylindrical tank supported in the holder and provided at the ends thereof with flanges abutting upon the ends of the holder. 80

2. A safety appliance for moving picture apparatus comprising a cylindrical holder composed of two hingedly connected members, one of said members having an aperture and the other member having a downward projecting tubular shank, in combination with an adjustably supported 85 arm engaging the tubular shank, means for securing the latter upon the arm, and a transparent cylindrical receptacle fitted in the holder and having a neck projecting through the aperture in the upper member of said holder. 90

3. A safety appliance for moving picture apparatus comprising a cylindrical tubular holder composed of two hingedly connected members provided with abutting flanges along their free edges, means for securing said flanges together, and a tank or receptacle of transparent glass fitted in the holder and containing a clear transparent liquid. 95

4. In a device of the class described, a tubular cylindrical holder having a downward projecting tubular shank provided with a set screw, a tank or receptacle of transparent glass supported in the holder and containing a clear transparent liquid, a supporting bracket, an arm having an eye engaging said bracket and provided with a set screw whereby it may be secured adjustably in position upon said bracket, said arm engaging the cylindrical shank of the holder, and a set screw extending through said cylindrical shank and serving to secure the latter adjustably upon the arm. 100

In testimony whereof, we affix our signatures in presence of two witnesses.

ARTHUR F. ELKINS.
HENRY HUNTER.
